THOMAS F. PAYNE, OF PITTSBURGH, PENNSYLVANIA.

APPARATUS FOR OPERATING FLUSHING-VALVES.

1,087,255.

Specification of Letters Patent.

Patented Feb. 17, 1914.

Application filed October 22, 1910. Serial No. 588,465.

To all whom it may concern:

Be it known that I, THOMAS F. PAYNE, residing at Pittsburgh, in the county of Allegheny and State of Pennsylvania, a citizen of the United States, have invented or discovered certain new and useful Improvements in Apparatus for Operating Flushing-Valves, of which improvements the following is a specification.

10 It is the object of the invention to provide an apparatus for operating the discharge valve of a tank for flushing water-closets, or other like purpose, which shall be simple in construction and easily operated.

15 In the accompanying drawings forming part of this specification, the invention is illustrated in its preferred form, as applied to a water-closet tank of the well known "low-down" type. Since any well known 20 or suitable means may be employed for refilling the tank, such for example as any common form of automatic float-valve, illustration thereof is omitted.

25 Figure 1 is a top plan view of a tank with the cover removed, equipped with said preferred apparatus. Fig. 2 is a front elevation on the line II-II of Fig. 1. Fig. 3 is a detail elevational view of the valve-lever and operating cam.

30 The discharge of water from the tank is controlled by the valve 1, of the usual or any suitable form, which is normally held, by its own weight and that of the water above, upon the seat 2 in the orifice of the 35 discharge-pipe 30, leading to the closet-bowl. The valve is raised off its seat by means of a lever-arm 3, pivoted upon a pin 4, mounted on a bracket 5 secured to the wall of the tank, and connected at its free end to the 40 valve by the rods 6 and 7, the latter being preferably guided in the guide-piece 8, fastened to the tank or to the overflow pipe 9, as is usual.

45 In order to elevate the lever-arm 3 and open the valve, a cam 10 is arranged beneath the arm, between its pivotal point and its free end. The cam 10 is fastened to a shaft or spindle 11, which passes through the wall of the tank, and is provided outside the 50 tank with an operating handle 12.

In order to open any common form of flushing-valve which is held upon its seat by the pressure of water above it, the amount of energy expended in unseating the valve 55 and giving it its initial movement is materially greater than that required to move it

farther and to hold it open. This is particularly true of the type of closet-flushing valve now commonly used. As shown, it is usually of spherical form and hollow, and is formed, at least on its lower exterior surface, of an elastic material, in order to maintain a tight closure upon its seat. It is often lighter than the volume of water which it displaces, so that when raised it is borne up 60 by the water surrounding it until the water-level approaches that of the discharge-orifice. In order therefore to unseat the valve and give it its initial movement, there must be overcome first its own inertia accentuated 65 by its elastic contact with its seat, and second the pressure of the water above. But the pressure diminishes as the water passes below the valve, and practically ceases when the valve has entirely cleared the orifice. 70 Hence I make the operating surface of the cam 10 of such shape as to materially facilitate the unseating and initial movement of the valve, as compared with its further movement. The cam is preferably a 75 double one, so that movement of the handle 12 in either direction will operate to raise the lever-arm, and the surface on each side of the spindle is so curved that the bearing-point of the cam upon the lever-arm gradually shifts away from the spindle the farther the cam is turned. Thus when the cam is in position of rest, the lever-arm will bear upon it at a point immediately above the spindle, and in the movement of the cam in 80 either direction, the farther it is moved, the more remote from the spindle will be the bearing-point of the lever-arm. Thus the handle 12, spindle 11 and cam 10 form in effect a lever, in which the length of the 85 work-arm relatively to the power-arm gradually increases. During the initial movement of the handle the work-arm is relatively short, and hence most effective for unseating the valve with a minimum expenditure of energy; while as the valve is lifted the effectiveness of the work-arm for the same energy proportionately decreases. 90

95 Since as herein shown the spindle stands somewhat nearer to the pivotal point of the 100 lever-arm than to its free end, the curvature of the cam on the side of the spindle toward the pivotal point is more abrupt than on the opposite side. It is preferred to form a flat surface on the cam immediately above the 105 spindle, as indicated at 10^a, as a bearing for the lever-arm when inactive, so that the 110

weight of the lever-arm will assist in holding the cam in central position; but that is not essential. Also it is apparent that the handle 12 may be swung in one direction 5 only, and the cam be arranged only on that side of the spindle. Stops 16 and 17 are preferably provided on the lever-arm and the bracket 5 respectively to limit the upward movement of the lever-arm.

10 The operation of the apparatus is clearly shown in Fig. 3, in which is shown in full lines the position of the handle and cam when the handle is swung to the right, and in dotted lines their position when the handle is swung to the left, the lever being lifted to the same extent by the same movement 15 of the handle in either direction.

Many changes may be made in the particular apparatus herein shown and described 20 without departure from the essential features of the invention as defined in the claim hereto appended.

I claim as my invention:

In an apparatus for operating flushing-valves, the combination with a vertically 25 movable flushing-valve, and a horizontal lever-arm connected thereto, of a cam for moving the lever-arm pivoted adjacent thereto and having a convex curved configuration such that when the cam is moved 30 the point of contact on the lever-arm gradually shifts from a position in a vertical line with the pivotal point of the cam to a lateral and more remote position from the said pivotal point, whereby the initial movement of the lever-arm may be effected with 35 a minimum effort.

In testimony whereof, I have hereunto set my hand.

THOMAS F. PAYNE.
